CLAIM

The ornamental design for a motorcycle tire, as shown and
described.

DESCRIPTION

FIG. 1 is a perspective view of a motorcycle tire showing my
new design;

FIG. 2 is a front view thereof, the back view being a mirror
image thereof;

FIG. 3 is a top view thereof, the bottom view being identical;

FIG. 4 is a right side view thereof;

FIG. 5 is a left side view thereof;

FIG. 6 is a fragmentary enlarged front view; and,

FIG. 7 is an end view taken along line 7-7 in FIG. 6.

Broken lines show environmental portions of a tire that are
not being claimed, and form no part of the claimed design.
The light stippled surface shading represents the surface of
the tire tread, and the dark stippled surface shading repre-
sents the recessed portion of the tread grooves, having the
depth as shown in FIG. 7.
